UNITED STATES PATENT OFFICE.

RICHARD C. LAMBERT, OF HOLBROOK, MASSACHUSETTS, ASSIGNOR OF ONE-HALF TO MICHA B. FAXON, OF SAME PLACE.

HORSESHOE-NAIL MACHINE.

SPECIFICATION forming part of Letters Patent No. 530,596, dated December 11, 1894.

Application filed June 18, 1894. Serial No. 614,843. (No model.)

To all whom it may concern:

Be it known that I, RICHARD C. LAMBERT, of Holbrook, in the county of Norfolk and State of Massachusetts, have invented certain new and useful Improvements in Horseshoe-Nail Machines, of which the following, taken in connection with the accompanying drawings, is a specification.

My invention relates to machines for making horse shoe nails and it consists in certain novel features of construction, arrangement and combination of parts which will be readily understood by reference to the description of the accompanying drawings and to the claims hereto appended and in which my invention is clearly pointed out.

Figure 1 of the drawings is a side elevation of a machine illustrating my invention. Fig. 2 is a sectional plan of the same the cutting plane being on line 1, 1, on Fig. 1. Fig. 3 is a vertical transverse section on line 2, 2, on Fig. 1 with the two side connecting rods shown in elevation. Fig. 4 is a partial sectional elevation, the cutting plane being on line 3, 3 on Fig. 2. Fig. 5 is a plan of one set of the swaging dies removed from the machine but in their relative positions when opened. Figs. 6, and 7, are respectively a plan and an end view of one of the fulcrum pins upon which the die operating levers are mounted.

In the drawings A is the bed or table of the machine supported upon suitable legs B, B, and having mounted thereon and firmly secured thereto the arch like slotted frame C provided at one end with the boxes or bearings C', C' in which is mounted the shaft D having firmly secured thereon the driving pulley E and eccentric cams F and F' as shown.

40 The frame C is slotted vertically so as to divide it, for a large part of its length, into two parts with sufficient space between said parts for the passage of the three armed levers G and G' fulcrumed upon a common non-revoluble fulcrum pin a and connected at their upper ends by the toggle links G² and G³ and having adjustably set in their lower ends the swaging dies b and b' respectively.

The table A is provided upon its upper side

with two boxes c and c' in which is mounted 50 in a fixed position the fulcrum pin d upon which are mounted the two levers H and H' connected together at their lower ends by the toggle links H² and H³ which are connected together and to the lower end of the two side 55 rods I and I', the upper ends of which are connected to each of the toggle links G² and G³ by a common pivot pin e as shown.

The upper ends of the levers H and H' have adjustably set therein the swaging dies 60 f and f' respectively said levers H and H' having their upper arms slotted for the passage of the dies b and b' carried by the levers G and G', and the lower arms of the levers G and G' are slotted for the passage of the set 65 screws f² and f³ for adjusting the dies f and f' all as shown in Fig. 4.

J is a three armed lever mounted upon a fulcrum pin g set in the frame C with the inner end of two of its arms pivoted to the side 70 rods I and I' at or near the middle of their lengths while the other arm projects through the slot of said frame C toward the right of Fig. 1 and has formed therein a large slot or oblong opening h to receive the eccentric cam 75 F which acts thereon to vibrate said lever and move the side rods I and I' up and down and thus straighten and break the toggles G² G³ and H² H³ as the shaft D is revolved.

The frame C has formed upon its upper 80 edge suitable housings and boxes in which are mounted the feed rolls i and i' the roll i having connected thereto the ratchet wheel i² which is engaged by the pawl j adjustably pivoted to the lever J and pressed into engagement with the teeth of the ratchet wheel i² by the spring k as shown in Fig. 2 and in dotted lines in Fig. 1.

The table A has formed upon or secured to its under side two boxes l and l' in bearings 90 in which is mounted in a fixed position the fulcrum pin m upon which are mounted so as to oscillate thereon the levers K and K' connected together at their lower ends by the toggle links K² and K³ and each having adjustably set in its upper arm two swaging dies n and n' constructed and arranged to co-operate with the dies b, b', and f, f', to

swage the bar of iron into the shape of a horse shoe nail. The dies $n' n'$ have secured to their upper sides the chisel shaped cutters o, o , which co-operate to sever the nail from the rod at the same time that the lower set of dies are completing the shaping of the nail.

The inner ends of the toggle links K^2 and K^3 are connected together and to the short coupling link L by the pivot pin p , the lower end of said link L being pivoted at p' to the lower arm of the elbow lever M mounted upon the fulcrum pin q mounted in ears formed upon or secured to the leg B at the right hand end of Fig. 1. The lever M is moved about its fulcrum in one direction to straighten the toggle $K^2 K^3$ by the action of the cam F' upon the upright arm of said lever, and in the opposite direction to break the toggle by the spring r shown only in dotted lines in Fig. 1. The fulcrum pins a, d , and m are made preferably with square journals or shanks s, s , to rest in correspondingly shaped bearings to prevent their being revolved, with two cylindrical sections s', s' , to receive the levers to be carried thereby and with a central collar s^2 of larger diameter than the sections $s' s'$ and has formed therein the hole t which extends diametrically through said collar in a vertical direction for the passage of the heated rod and in the case of the lower fulcrum pin m for the passage of the finished nail.

The feed roll i' is adjustable toward or from the roll i by means of the set-screws t' to adapt it to slight variations in the size of the rods used, and the feed rolls i and i' have circumferential grooves formed therein adapted to receive the edges of the rod or bar of iron from which the nails are to be formed as shown in Figs. 2 and 3.

The rod of iron from which the nails are to be formed is heated to the desired temperature in any suitable manner which may be done by a heating device, electric or otherwise upon the machine or detached therefrom as may be preferred, and suitable means not shown will be employed to keep the dies cool or at least prevent their becoming injuriously heated. The inner or operating faces of the several dies are so shaped that when closed or at the extreme of their inward movement there will be a space between the lower set of dies exactly corresponding in length and cross section to the finished nail and between the upper set of dies there will be a space of similar shape but somewhat larger than the finished nail.

The eccentric cams F and F' should be so placed upon the shaft D that the toggle K^2, K^3 , will be nearly straightened before the toggles $G^2 G^3$ and $H^2 H^3$ begin to straighten, or so that the dies n and n' will have completed their inward movement before the dies $b b'$ and ff' come in contact with the rod at which time the dies $b b'$ and ff' will be sup-

ported by the dies $n' n'$ and $n n$ respectively said dies $b b'$ and ff' having a cross section exactly corresponding in shape and size to the cross section of the space between the dies $n' n'$ and $n n$ respectively.

The lever J is slotted to receive the pivot pin upon which the pawl j is mounted, so that said pawl may be adjusted to a greater or less distance from the fulcrum of said lever J , to vary the stroke of said pawl, and thereby increase or diminish the length of rod fed at each revolution of the shaft D .

While I have shown and described only two sets of dies, each set composed of two pairs each, it is obvious that a greater number of sets of dies may be used without affecting the principles of my invention, and therefore I do not wish to be limited to the use of two sets of dies. It is also obvious that the dies must be made of different sizes according to the size of the nails to be made, and changeable at the will of the operator.

What I claim as new, and desire to secure by Letters Patent of the United States, is—

1. In a nail forging machine the combination of a pair of oppositely vibrating levers mounted upon a common axis; a swaging die mounted in each of said levers, below said axis of motion, with their working ends toward and near each other; a second pair of oppositely vibrating levers mounted upon a common axis and movable in a plane at right angles to the plane of movement of said first mentioned levers; a pair of dies carried by said second pair of levers at the ends thereof above their axis of motion, said dies being located in the same horizontal plane as, and arranged to co-operate with, said first mentioned pair of dies to swage the same section of the nail rod.

2. In a nail forging machine, the combination of a pair of intermittently revolving feed rolls for feeding the nail rod to the dies; a non revoluble fulcrum pin arranged directly beneath the space between the feed rolls, and provided with a vertical opening through the same for the passage of the nail-rod; a pair of die operating levers mounted upon said fulcrum-pin; a die adjustably set in one end of each of said levers, and co-operating with each other to swage opposite sides of the nail rod; a pair of toggle links connecting the other ends of said levers; and means having provision for alternately straightening and breaking said toggle, and thus cause said dies to act upon the nail-rod to change its shape.

3. The combination of the table A provided with the boxes $c c', l$ and l' ; the arched and slotted frame C provided with the boxes C', C' ; the feed rolls i and i' ; the shaft D ; the cams F and F' ; the fixed fulcrum pins a, d , and m ; the three pairs of levers $G G', H H'$ and $K K'$ mounted respectively on said pins a, d , and m ; the toggles $G^2 G^3, H^2 H^3$ and $K^2 K^3$; the dies $b b', ff', n$ and n' carried by said

levers and arranged relative to each other as set forth; the cutting off knives o, o ; the side rods or links I and I'; the three armed lever J; the elbow lever M; and the link L, all constructed, arranged and operating substantially as described.

In testimony whereof I have signed my

name to this specification, in the presence of two subscribing witnesses, on this 15th day of June, A. D. 1894.

RICHARD C. LAMBERT.
